UNITED STATES PATENT OFFICE

SIGMUND STERNAU, OF NEW YORK, N. Y., ASSIGNOR TO S. STERNAU & COMPANY, OF NEW YORK, N. Y., A COPARTNERSHIP.

DESIGN FOR A STAND.

41,687.

Specification for Design.

Patented Aug. 15, 1911.

Application filed July 11, 1910. Serial No. 571,504. Term of patent 7 years.

To all whom it may concern:

Be it known that I, SIGMUND STERNAU, a citizen of the United States, and a resident of the borough of Manhattan, city, county, and State of New York, have invented a new, original, and ornamental Design for a Stand, of which the following is a specification, reference being had to the accompanying drawing, forming part thereof.

The figure is a perspective view of a stand showing my new design.

The stand comprises a top 1, a shelf 2, and legs 3. The top is circular in plan, hav-

ing a depressed bowl-like center and an ornamental edge, as shown. The shelf is of circular plan, with a bowl-like center. The legs are rectangular, with slightly enlarged feet. Straps connect the legs to the shelf.

I claim:

The ornamental design for a stand, as shown and described.

SIGMUND STERNAU.
